UNITED STATES PATENT OFFICE.

ROGER B. FARQUHAR, JR., OF PHILADELPHIA, PENNSYLVANIA.

LOCOMOTIVE-FRAME.

1,159,200.

Specification of Letters Patent.

Patented Nov. 2, 1915.

Application filed July 22, 1914. Serial No. 852,422.

To all whom it may concern:

Be it known that I, ROGER B. FARQUHAR, Jr., a citizen of the United States, residing in Philadelphia, Pennsylvania, have invented 5 certain Improvements in Locomotive-Frames, of which the following is a specification.

My invention relates to improvements in the manufacture of frame structures, usually of truss form, such as are commonly used in locomotives, and one object of the invention is to provide a locomotive or similar frame of materially reduced weight for a given strength or capacity, the construction being such that said frame is relatively inexpensive to construct, both because of the reduced quantity of material required, as well as by reason of the lessened cost of manufacture.

20 A further object of the invention is to provide a locomotive frame which for given capacity or strength shall be comparatively light and require materially less machine work for its finishing operation than has hitherto been considered necessary, the construction being such that the frame is hollow and has its metal so disposed that its walls have no very thick portions, while in addition the exterior superficial area requiring machining is reduced.

25 The invention also contemplates a hollow locomotive frame having its outer surface so formed and treated as to materially increase its structural strength.

30 These objects and other advantageous ends I secure as hereinafter set forth, reference being had to the accompanying drawings, in which,

35 Figure 1 is a vertical section, on a reduced scale, illustrating a portion of a locomotive side frame constructed according to my invention; Fig. 2 is a section similar to that of Fig. 1, illustrating a portion of the frame on an enlarged scale; Figs. 3 to 7 inclusive are 40 transverse sections illustrating some of the forms in which the metal may be disposed in frames constructed according to my invention; Fig. 8 is a transverse section of a part of a mold illustrating one step in the manu- 45 facture of my improved frame; Figs. 9 and 10 are respectively a vertical section and a 50 side elevation of one form of collapsible core which may be employed in making the frames.

55 In carrying out my invention, I propose to cast such frames as those required for lo-

comotives in the form of a series of integral tubular or hollow members, and in the above drawings, 1 represents a portion of such a frame having a top member 2, a bottom member 3, and a series of vertical members 4, 5, 6, and 7, of which those indicated at 5 and 6 connect the ends of the bottom member with the top member. The lower ends of the vertical members 4 and 7 are shown 60 in the present instance as connected by diagonal members 8 and 9 with the opposite end portions of the top member 2, though obviously other constructions may be employed if desired. One characteristic feature of my 65 invention resides in the fact that all of these members are hollow, the tubular passages 10 formed in them being of any desired or suitable cross section. In Fig. 3, for example, the interior passage 10^a is of octagonal 70 form, while in Figs. 4 and 6 it is shown as octagonal and square respectively. In the case of Figs. 5 and 7, the passage through the frame members 1^a and 1^b is shown as 75 divided by longitudinally extending diagonal webs 11 and 11^a which lie substantially at right angles to each other. The passages may also be connected with the exterior surfaces of the frame by holes or openings, as 80 at 1^c, Fig. 6.

85 Another feature of the invention resides in forming the members of the frame with panels or depressions 12 extending longitudinally in the otherwise flat faces, it being noted that the bottoms of these panels do 90 not require to be machined after the frame is finished, as do the remaining outer parts of the frame surface, with the result that frames made according to my invention are 95 considerably less expensive than those made by other methods because of this lessened machine work. While ordinarily each frame member would have but a single longitudinal panel on each face, in some cases two or more may be employed as in Fig. 4. 100 It is to be noted that owing to the increase in exterior superficial area resulting from this paneled construction, there is a material increase in the strength of the frame due largely to the unbroken skin which is not 105 removed by the machining but is allowed to remain on the bottoms and sides of the panel depressions.

110 The invention also contemplates making the metal in the immediate vicinity of the panels finer grained and stronger than it would otherwise be, and for this purpose I

may cast the frame, which is of steel, in a mold having a body of sand 13 supporting the required number of chills 14 which are so placed as to affect the metal constituting the bottoms and sides of the panel portions of the frame 1. In the case shown in Fig. 8, the frame structure has its interior passage 10^b of circular section, the core structure 15 consisting of pipes suitably supported within the mold 13 and designed to be left permanently in place with the frame members.

If it be desired to remove the core from the passages of the frame members, any of a number of collapsible core devices may be employed. For example, in Fig. 9, I have illustrated a core designed to form a substantially square passage through the frame members and this is made of two substantially U-shaped pieces 16 and 17 of which the free edges of the latter have internal flanges 18 for the reception of the edges of the former. Between these two pairs of edges of said members I place masses 19 of readily fusible material such as metal or alloys thereof, designed to retain the parts 16 and 17 in the proper relative positions at the required distance apart. Under conditions of use, this core structure 16-17 is suitably supported in a mold with its various parts in the desired positions, and the metal for the frame is cast around the same. The heat from this metal causes melting of the strips 19 so that the part 16 of the core moves toward the part 17, thus releasing both core members and permitting them to be easily withdrawn after the metal has solidified. It is to be understood that in using such a core it is protected from direct contact with the molten metal by any suitable material such as sand or the like and has perforations 20 in its faces to permit of the escape of any steam and gas which may be formed.

After the frame has been cast it is subjected to a suitable heat treatment whereby it is given the desired characteristics required of such a structure. In this process it is first uniformly heated to the proper temperature to remove all initial internal strains and refine the grain, such temperature being governed by the critical points of the particular composition of steel used, and may vary from 50°, to 150° C. above such points. The frame is then quenched in air, oil, water, or other medium to not below 200° C., the medium used depending upon the desired ratio of hardness to ductility, this ratio in turn being dependent upon the rapidity with which the quenching is accomplished, air being the slowest and water the quickest quenching agency. The parts are then reheated and annealed or "drawn" at a temperature of not less than 500° nor more than 700° C., again depend-

ing upon the composition of the steel and the physical properties desired, after which they are allowed to cool in the air or the furnace to atmospheric temperature. This second reheating or annealing, sometimes called "drawing" is to remove any injurious strains that may be set up by the quenching, and to further refine and toughen the steel.

From the above description it will be obvious that a locomotive or other frame made as described is of materially increased strength for a given weight of metal, or for a given strength, requires considerably less material than frames previously made. Moreover, by the provision of the longitudinally extending passages and surface depressions or panels, the time required for cooling in the mold may be decreased at will by forcing air, water, etc., through the cores, thus improving the initial structure of the casting and also making possible a decrease in the time for subsequent reheating and quenching.

It is of the most profound importance that the drop in temperature due to the "quench" may rapidly reach every particle or molecule of the casting, if the grain or structure of the steel is to be put into the strongest and finest possible condition and hitherto I have found that a sudden quench can only be uniformly and completely effected by a depth of 2" or less. Hence the great value of the exterior recesses or panels and cored passages, which insure practically a uniform and even treatment and grain structure in all parts of the section, and greatly diminish the likelihood of injurious internal stresses,—results not possible of accomplishment with the thick frame sections now commonly used. Furthermore, the strength of the members is increased by chilling localized portions.

I claim:

1. A locomotive frame consisting of a series of integrally connected hollow members; with tubular core members permanently mounted within said members.

2. A locomotive frame consisting of a series of integrally connected members having longitudinally extending depressions in their faces, the high portions of the surface of said members being finished and the depressed portions of said surfaces being unfinished.

3. A locomotive frame consisting of a series of integrally connected tubular members having portions of their internal surfaces chilled.

4. A locomotive frame consisting of a series of integrally connected members having longitudinally extending paneled depressions, the metal adjacent to said depressions being chilled.

5. A locomotive frame consisting of a casting consisting of a series of members

all having central longitudinally extending passages of geometric section and longitudinally extending paneled depressions formed in the external faces of said members.

6. A locomotive frame consisting of a casting consisting of a series of members all having central longitudinally extending passages of geometric section and longitudinally extending paneled depressions formed in the external faces of said members, there

being horizontally extending holes connecting the exterior surfaces with the interior passages.

In testimony whereof, I have signed my name to this specification, in the presence of two subscribing witnesses.
